[57] CLAIM

The ornamental design for a printer control device, as shown and described.

DESCRIPTION

FIG. 1 is a perspective view of a printer control device in an exploded condition showing my new design, the hand depicted by means of broken lines being for illustrative purposes only and forming no part of the claimed design. FIG. 2 is a perspective view illustrating my new printer control device design;

FIG. 3 is a front elevational view;

FIG. 4 is a rear elevational view;

FIG. 5 is a top plan view;

FIG. 6 is a bottom plan view;

FIG. 7 is a right side elevational view; and,

FIG. 8 is a left side elevational view.
